UNITED STATES PATENT OFFICE.

PATRICK KAVANAGH, OF MILFORD, MASSACHUSETTS, ASSIGNOR TO DRAPER CORPORATION, OF HOPEDALE, MASSACHUSETTS, A CORPORATION OF MAINE.

AUTOMATICALLY-THREADING LOOM SHUTTLE.

Application filed October 2, 1924. Serial No. 741,129.

To all whom it may concern:

Be it known that I, PATRICK KAVANAGH, a citizen of the United States, and a resident of Milford, in the county of Worcester and State of Massachusetts, have invented an Improvement in Automatically-Threaded Loom Shuttles, of which the following description, in connection with the accompanying drawings, is a specification, like characters on the drawings representing like parts.

This invention relates to automatically threading loom shuttles employed in looms wherein the weft or filling thread is automatically replenished from time to time.

It is now the common practice to provide automatically threading loom shuttles with various forms of horns or overhangs or guards which prevent the free exit of the thread from the threading device when once the shuttle has been threaded, and in some cases the obstructing horns or overhangs have been associated with scroll eyes to facilitate shuttle threading and as an additional security against subsequent unthreading.

During the operation of the loom when the shuttle is arrested in the replenishing box, the weft or filling thread is liable to overthrow or balloon or loop, with the result that in the now prevailing forms of loom shuttles, the loop or overthrow is liable to become caught on some part of the threading device and be broken on the subsequent pick.

In the patent to Edward S. Stimpson, No. 1,483,492, dated February 12, 1924, is shown and described an automatically threading loom shuttle wherein on the occurrence of a loop or overthrow, the shuttle will become partially or wholly unthreaded, and will again become threaded on subsequent picks of the shuttle. The present invention is a further development of the automatically threading shuttle shown and described in the Stimpson patent, and is more particularly directed to means for facilitating the return of the weft or filling thread to the control of the threading device as the shuttle is picked after it has been unthreaded or partially unthreaded. When the shuttle is wholly or partially unthreaded and is picked, the whirling action of the thread as it unwinds from the filling carrier or bobbin in the

shuttle is in a direction reverse of the wind of the thread on the filling carrier or bobbin. Usually the filling carriers or bobbins have the filling wound thereon in a direction contra clockwise, viewing the bobbin or filling carrier from the tip end thereof, and when the filling is unwound during the flight of the shuttle, the unwinding thread takes a course clockwise of the filling carrier or bobbin at the tip end. This condition is fully disclosed in the Stimpson patent. In some cases, however, the filling is wound in the reverse direction upon the filling carrier or bobbin, that is, looking at the tip end of the filling carrier, the filling is wound in a clockwise direction, so that when the filling unwinds as the shuttle is picked, it will whirl in a contra-clockwise direction.

One of the objects of the present invention, therefore, is to provide an automatically threading loom shuttle of the thread casting type, such as shown and described in the Stimpson patent, that it may be employed with a reversely or left-wound bobbin. Another object of the invention is to provide in a shuttle of the thread casting type, such as disclosed in the Stimpson patent, additional means cooperating with the whirling thread as it is unwound from the bobbin when the shuttle is picked, to insure that the whirling thread will pass into control of the thread casting and guiding device. This latter feature may be advantageously utilized in shuttles using either the right or left-wound filling carriers or bobbins.

The invention and various new combinations of parts will best be made clear from the following description and the accompanying drawings of one good form thereof.

In the drawings:

Fig. 1 is a perspective view of an automatically threading shuttle of the thread casting type having the present invention associated therewith, and shown as employed in connection with a reversely or left-wound bobbin, part of the shuttle being broken away;

Fig. 2 is a perspective detached detail showing a threading block containing the present invention;

Fig. 3 is an enlarged longitudinal section through the threading block and thread

105

110

casting device employed in connection with a left-wound or reversely-wound bobbin;

Fig. 4 is an end view looking from the left of Fig. 3;

5 Fig. 5 is a cross-section of a shuttle and threading device looking towards the threading end of the shuttle containing the present invention, and more especially adapted for use in connection with reverse 10 or left-wound bobbins; and

Fig. 6 is a front view similar to that of Fig. 4, but showing the thread casting and guiding device and thread guiding means for use in connection with the usual right- 15 wound bobbin.

The shuttle 1 is provided with the usual bobbin chamber 2 in which is supported the usual filling carrier or bobbin 3. The means for detachably holding the filling carrier or 20 bobbin in the shuttle, as by use of the bobbin holding jaws, is not herein shown because it forms no part of the present invention.

The shuttle 1 is provided with a threading 25 block receiving chamber 4 formed in the front end of the shuttle, and a front- wardly extending recess 5. Communicating with the longitudinally extending thread passage, which is shown as formed in the 30 threading block, the shuttle is provided with a side delivery eye 6.

The threading block 7 has the side walls 8 and 9 formed to fit the side walls of the threading block receiving chamber 4, and 35 at the side of the threading block adjacent the side delivery eye 6 of the shuttle is the thread director 10, the tip end portion 11 of which is turned laterally with a tapering end constructed and arranged to 40 shed any loop or thread that may be caught thereon, as more fully explained in the Stimpson patent hereinbefore referred to.

The threading block 7 has the longitudinally extending thread passage 12 which 45 is substantially unobstructed by any overhang, guard or similar device which would interfere with the ready exit or entrance of the thread.

As shown in Fig. 1, the filling carrier or 50 bobbin 3 has the filling 13 wound thereon in a clockwise direction looking towards the tip of the filling carrier or bobbin, and consequently as the weft or filling thread *a* is drawn from the filling carrier or bobbin 55 when the shuttle is picked, the filling thread takes a course in a direction substantially as indicated by the arrow in Fig. 5. Mounted in the thread passage is the thread casting and guiding device 14 which, as shown, 60 extends from the side of the thread passage opposite the side delivery eye 6 and thread director 11, with the result that when the filling thread *a* is withdrawn from the bobbin as the shuttle is picked, the course 65 of the thread will correspond to the gen-

eral curve of the thread casting and guiding device 14.

The thread casting and guiding device 14 has an upwardly, laterally and frontwardly extending thread casting portion 15 which 70 starts preferably at a point adjacent the bobbin chamber, the construction being such that on the formation of a loop or overthrow when the shuttle is arrested at the end of its flight, the weft or filling thread *a* 75 will engage the upwardly, laterally and frontwardly extending edge 15 and be thrown from the thread casting device upwardly and, it may be, entirely out of the longitudinally extending thread passage. 80

As shown in the present instance of the invention, the thread casting and guiding device 14 has a base portion 16 which extends downwardly into the receiving recess 17 of the threading block, and its lower edge portion is preferably turned laterally, as at 18, to provide a firm and steady bearing 85 at the under side of the threading block. With the construction described, the thread casting and guiding device 14 as well as 90 the threading block 7 may be advantageously and conveniently secured in the shuttle by the usual cross-bolt 19.

The thread casting and guiding device 95 14 is conveniently formed as a scroll, as shown, the frontwardly extending edge portion 20 of which extends frontwardly in the thread passage, substantially as shown and described in the Stimpson patent, hereinbefore mentioned, with the exception that the thread casting and guiding device when used with a left-wound or reversely wound bobbin is located in the thread passage, so that the thread casting portion 15 thereof 100 starts at a point at the left of the thread passage and extends upwardly, laterally and frontwardly therefrom, to thereby cast the thread of the reversely or left-wound bobbin 105 when a loop or overthrow occurs as the shuttle is arrested at the end of its flight. 110

The threading block 7 has a bridge portion 21 over which the thread is drawn when the shuttle is picked, and frontwardly of the bridge portion 21 is a horn or deflector 115 22 below which the thread passes, as indicated in Fig. 1, when the shuttle is fully threaded and the thread is being delivered from the side delivery eye.

As hereinbefore noted, the weft or filling thread *a* as it is drawn from the filling 120 carrier or bobbin during the flight of the shuttle, whirls in a path determined by the wind of the thread upon the filling carrier or bobbin, and an important feature of the present invention, therefore, consists in a 125 guide located in the thread passage for directing the thread into the control of the thread casting and guiding device as the wholly or partially unthreaded shuttle is 130 picked.

Where the filling is wound upon a filling carrier or bobbin with a reverse wind, as indicated in Figs. 1 and 5, the whirling action of the thread carries it in a path indicated by the arrow *b* and the radiating lines *c*, Fig. 5. The thread guide indicated at 23 extends from the side of the thread passage preferably in a downwardly inclined direction, Fig. 5, towards that side from which

5 the thread casting and guiding device assumes its initial position. In the case of a reversely or left-wound bobbin, as indicated in Fig. 5, as the thread whirls in the direction of the arrow *b* it will strike the guide 23 and be by it directed into control of the thread casting and guiding device, finally assuming the position as indicated at *a*, Fig. 5.

In case the thread casting and guiding device is employed with a bobbin having the usual or right-hand wind, the guide 23 is located as indicated in Fig. 6, that is, it extends downwardly in an inclined direction from the side of the thread passage towards

20 the opposite side thereof to which the thread casting and guiding device is secured, so that in the whirling action of the thread from the usual wound bobbin, the guide 23 will direct the thread into control of the thread casting and guiding device.

When the thread casting and guiding device is employed in connection with a reversely or left-wound bobbin, as indicated in Fig. 1, the thread casting portion 15 starts from a point preferably adjacent the bobbin chamber in an upwardly, laterally and frontwardly extending direction from the left side of the thread passage, and the guide 23 extends from the opposite side of

35 the thread passage in an inclined downwardly direction to direct the whirling thread into control of the thread casting and guiding device.

Where the thread casting and guiding device is employed in connection with a right-wound bobbin, as indicated in Fig. 6, it will be secured in the thread passage with its thread casting portion 15 extending upwardly, laterally and frontwardly from the

50 right side of the thread passage and the guide 23 will extend from the opposite side of the thread passage in a downwardly inclined direction, as indicated in Fig. 6, the effect being that the guide 23 whether used with a right or left wound bobbin will direct the thread more accurately into control of the thread casting and guiding device as the wholly or partially unthreaded shuttle is picked.

60 What is claimed is:

1. An automatically threading loom shuttle having a thread passage extending longitudinally thereof, a side delivery eye communicating with the thread passage, a thread casting and guiding device in the

thread passage constructed and arranged to cast the thread and partially or wholly unthread the shuttle on the occurrence of an overthrow as the shuttle is arrested at the end of its flight, and a guide between the 70 thread casting and guiding device and the side delivery eye for directing the thread into the said device as the unthreaded shuttle is picked.

2. In an automatically threading loom shuttle having a thread passage extending longitudinally thereof, a side delivery eye communicating with the thread passage, a thread casting and guiding device in the thread passage constructed and arranged to cast the thread and partially or wholly unthread the shuttle on the occurrence of an overthrow as the shuttle is arrested at the end of its flight, and a guide in the thread passage between the casting and 80 guiding device and the side delivery eye for directing the whirling thread into the control of said device as the unthreaded shuttle is picked.

3. An automatically threading loom shuttle having the wood of the shuttle cut away to form a threading block receiving chamber and side delivery eye, in combination with a threading block secured in said chamber and having a thread passage, a 90 thread casting and guiding device secured at one side of the threading block for casting the thread on the occurrence of a loop or overthrow to partially or wholly unthread the shuttle, and a guide in the thread passage at the opposite side thereof for directing the whirling thread into control of said device as the partially or wholly unthreaded shuttle is again picked.

4. An automatically threading loom shuttle having the wood of the shuttle cut away to form a threading block receiving chamber and side delivery eye, in combination with a threading block secured in said chamber and having a thread passage, a thread casting and guiding device secured at one side of the threading block and having a thread casting portion which extends upwardly, laterally and frontwardly from a point adjacent the bobbin chamber for casting the thread from said device and partially or wholly unthreading the shuttle on the occurrence of an overthrow, and a guide in the thread passage at the opposite side thereof for directing the whirling thread into the control of said device as the partially or wholly unthreaded shuttle is again picked.

5. An automatically threading loom shuttle having a longitudinally extending thread passage, a side delivery eye, a thread casting and guiding device in the thread passage having a thread casting portion extending upwardly, laterally, and frontwardly from the side of the thread passage opposite the 125

- side delivery eye for casting the thread of a bobbin on the occurrence of a loop or overthrow to partially or wholly unthread the shuttle as the shuttle is arrested at the end 35 of its flight and a guide in the thread passage at the side opposite the thread casting and guiding device for directing the whirling thread into the control of said device.
8. An automatically threading loom shuttle having a threading block provided with a longitudinally extending thread passage 40 with an open top for ready entrance and exit of the thread, a side delivery eye, a thread casting and guiding device having a thread casting portion adjacent the bobbin chamber at the side thereof opposite the delivery eye for casting the thread of a 45 reversely wound bobbin and partially or wholly unthreading the shuttle on the occurrence of a loop or overthrow when the shuttle is arrested at the end of its flight. 50
9. An automatically threading loom shuttle having a threading block provided with a longitudinally extending thread passage and a thread director projecting from one side thereof, and a thread casting and guiding device having a thread casting portion extending from the opposite side thereof for casting the thread of a left wound bobbin and partially or wholly unthreading the shuttle on the occurrence of a loop or overthrow as the shuttle is arrested at the end of its flight. 55
7. An automatically threading loom shuttle having a longitudinally extending thread passage, a side delivery eye, a thread casting and guiding device in the thread passage having a thread casting portion extending upwardly, laterally, and frontwardly 60 from the side of the thread passage opposite the side delivery eye for casting the thread of a reversely wound bobbin to partially or wholly unthread the shuttle on the occurrence of a loop or overthrow as the shuttle is arrested at the end of its flight.
- 30 8. An automatically threading loom shuttle having a longitudinally extending thread passage, a side delivery eye, a thread casting and guiding device in the thread passage having a thread casting portion extending upwardly, laterally, and frontwardly from the left side of the thread passage for casting the thread of a left wound bobbin on the occurrence of a loop or overthrow to partially or wholly unthread the shuttle as the shuttle is arrested at the end of its flight, and a guide between the thread casting and guiding device and the side delivery eye to

In testimony whereof, I have signed my name to this specification.

PATRICK KAVANAGH.
